UNITED STATES PATENT OFFICE.

FREDERICK H. PERRY, OF BEVERLY, MASSACHUSETTS, ASSIGNOR TO UNITED SHOE MACHINERY CORPORATION, OF PATERSON, NEW JERSEY, A CORPORATION OF NEW JERSEY.

EDGE-TRIMMING MACHINE.

Application filed May 31, 1919. Serial No. 300,804.

To all whom it may concern:

Be it known that I, FREDERICK H. PERRY, a citizen of the United States, residing at Beverly, in the county of Essex and State of Massachusetts, have invented certain Improvements in Edge-Trimming Machines, of which the following description, in connection with the accompanying drawings, is a specification, like reference characters 10 on the drawings indicating like parts in the several figures.

This invention relates to machines for operating on shoe soles, and is herein disclosed as embodied in a machine known in 15 the shoe-manufacturing art as a jointing machine.

As a step in shoemaking, it is customary, after the wear sole and upper have been permanently connected, to trim the edge of 20 the sole to the desired contour, and for this purpose the sole is subjected to successive trimming instrumentalities each having an effective profile formed according to the particular portion of the sole upon which it 25 is to operate. For example, a trimming tool of one profile is used to trim the edge around the forepart where a square edge is desired, and a trimming tool of another profile is used to trim the inner edge along 30 the shank portion where a curved or undercut edge is desired. The shank-trimming operation along the inner edge should end at the breast of the heel, and, in order to avoid carrying it beyond such point, the 35 operation requires a form of trimming tool different from that used to trim other portions of the sole. Furthermore, the trimming of the inner edge of the shank requires different manipulation of the shoe, 40 due in part to the concavity of that edge, and due in part to the requirement that this part of the trimming should never progress beyond the breast of the heel. A rotary edge-trimmer is ordinarily used to trim 45 around the forepart, and one of another contour is used to trim the inner edge of the shank, but a rotary cutter will not trim to the breast of the heel without gouging the heel. Consequently, in recent years, so-called jointing machines have been used to 50 a large extent to complete the trimming of the shank between the farthest point reached by the rotary cutter and the breast

of the heel. Jointing machines designed especially for this purpose, and provided 55 with reciprocating shaving knives are disclosed in United States Letters Patent No. 1,030,605, granted June 25, 1912, and No. 1,108,225, granted August 25, 1914.

Machines of the type shown by said Letters Patent are provided with a double-edged shaving knife constructed and arranged to shave the inner edges of the shanks of right and left shoes, and with two chopping knives, one of which is brought into 60 operation only when the machine is used to trim the inner edge of a right shoe, and the other of which is brought into operation only when the machine is used to trim the inner edge of a left shoe. The supposed 65 necessity for two chopping knives arose from the fact that the heel of the shoe advances from right to left when operating upon the right side, and advances from left to right when operating upon the left side. 70 In each case the function of the chopping knife is to sever the shaving at the breast of the heel, and it is obvious that only one chopping knife is necessary at any one time. The presence of the other chopping knife 75 puts the user of the machine under the necessity of manipulating the shoe, in order to avoid injuring it, so that the extra chopping knife may not touch the shoe. The 80 difficulty of avoiding contact with the extra knife is relatively great when operating upon an edge that has a pronounced incurve, and also in the case of shoes that have comparatively short shanks. In order to avoid 85 interference when using the patented machines it is necessary to tilt the shoe so as to hold the forward part thereof away from the extra chopping knife. This condition 90 not only divides the attention of the user between the operation to be performed and the matter of keeping the forward part of the shank clear of the extra chopping knife, 95 but it diverts the trimming from the desired path.

One object of the present invention is to 100 overcome the difficulties incidental to the presence of two chopping knives, and this is accomplished, according to the illustrated embodiment of the invention, by an organization comprising only one chopping knife 105 in combination with a reciprocating shav-

ing knife. In order, however, to utilize a single chopping knife on both right and left edges the invention includes mechanism for shifting the chopping knife in opposite directions transversely of its lines of chopping movement so that it may operate in one path to sever the shaving from a right edge, and in another path to sever the shaving from a left edge.

10 Another object of the invention is to facilitate the transverse shifting of the chopping knife so as to relieve the user from special effort, mental or physical, incidentally to moving the chopping knife to the desired path of operation. In the illustrated machine this is accomplished by shifting mechanism arranged to be actuated in consequence of moving the breast of the heel against one of two feelers arranged to occupy positions where one of them will be displaced by a heel moving from right to left, and where the other will be displaced by a heel moving from left to right. In any case, the chopping knife, when fully shifted, will traverse a path of chopping movement coincident with the limit to which the then operating edge of the shaving knife is capable of moving, so that the shaving cut and the chopping cut will be coterminous.

Another object of the invention is to provide means for preventing the chopping knife from operating in any lines other than those in which the chopping cut will be coterminous with the shaving cut and coincident with the breast of the heel. In the present embodiment shown for the purpose of illustration, this object is fulfilled by means arranged to lock the chopping mechanism against operating excepting when it is in one of its two predetermined paths of operation, the locking means being controlled by the shifting mechanism so as to release the chopping mechanism when, and only when, the chopping knife has been fully shifted to one or the other of said paths.

The majority of heel-breasts, if not all of them, are pitched, that is to say, inclined from perpendicular relation to the tread surface. In order, therefore, to chop the shaving on an angle corresponding to the pitch of the breast an object of this invention is to alter the angle of the chopping knife whenever occasion requires, as when changing from the right side of a left shoe to the left side of a right shoe. In the machine illustrated this alteration of angle is effected by mounting the chopping knife so that its lateral movement from one path of operation to the other will include a component of angular movement.

A further object of the invention is to return the chopping knife automatically after every chopping operation to an intermediate position between its two predeter-

mined paths of operation, so that it will be normally inert and out of the field of observation of the shaving operation.

Other objects and improvements in construction are shown by the drawings and 70 are hereinafter described and claimed.

Referring to the accompanying drawings in which a preferred embodiment of the invention for a specific kind of operation is shown,—

75 Fig. 1 represents an elevation partly in section, of the right-hand side of the head of the machine designed for trimming the shanks of soles. According to this figure the front of the machine is at the left; 80

Fig. 2 represents a top plan view of the head, a portion of the frame being broken away to disclose gearing contained therein. According to this figure the chopping knife occupies its median position where it is 85 locked with respect to chopping movement;

Fig. 3 represents a perspective view including the chopping knife, the laterally movable guide in which it is arranged to slide, and some elements of the mechanism 90 by which the guide is shifted from side to side;

Fig. 4 represents a front elevation including the right and left actuating hammers for the chopping knife together with their 95 respective locking members by which they are prevented from operating when the chopping knife occupies an intermediate position between predetermined paths of chopping movement; and 100

Fig. 5 represents a front elevation of the shaving knife and the chopping knife, including dotted lines indicating the path traversed by the shaving knife and dotted lines indicating the predetermined paths of 105 operating movement of the chopping knife.

Referring first to Fig. 1, the frame of the head is indicated at 10, and a continuously rotating shaft is indicated at 12. The head provides a bearing for the shaft, and the latter may be driven by any suitable means, not shown. The head is provided with a coupling flange 14 by which it may be fixed to a standard or other suitable support.

The shaving knife is indicated at 16, and 115 it is provided with a shank by which it is affixed detachably to a holder 18. The holder, in turn, is affixed to an oscillatory carrier 20, a bolt 22 serving to clamp the holder against the forward end of the carrier and dowels 24 serving to fix the holder to the carrier with respect to turning about the axis of the bolt. The carrier is mounted upon a spindle 26 relatively to which it is capable of oscillating. The rear end of this 120 spindle is fixed to the frame 10 of the head as shown by dotted lines. A shoulder 27 formed on the carrier bears against a hardened steel block 29 and is thereby prevented from sliding endwise on the spindle. The 125 130

block 29 is fixed to the frame 10 by a clamping screw 31. A yoke 28 formed upon the carrier carries a bushing 30 that has sliding fit therein and a running fit on the raised pin 5 32 carried by the shaft 12. This mechanism serves to oscillate the shaving knife edge-wise, the path traversed by the knife being substantially horizontal.

Referring to Fig. 5, the shaving knife is 10 shown as having two cutting edges 34 and 36 at its ends respectively, and the limits to which the knife moves are indicated by dotted lines. As shown by Fig. 1, the shaving knife is curved in cross section so that 15 it will form a convex edge on the work. A guide for guiding the work relatively to the knife is indicated at 38 in Fig. 1, the lower end of said guide being arranged to occupy the groove or crease between the 20 upper and the extension of the sole.

The chopping knife is indicated at 40 and it is detachably secured to the lower end of a holder 42, the latter being split at its lower end to provide relatively movable clamping 25 portions, and being provided with a clamping bolt 44 arranged to tighten said clamping portions against the knife to hold the latter rigidly. The holder 42 is arranged to slide vertically in a guide or carrier 46, the 30 upper end of the holder extending above the guide to provide connection with the actuators that impart chopping movement to the knife. The holder 42 is angular in cross section, as shown by Figs. 2 and 3, 35 to prevent it from turning about its axis relatively to the guide. The guide is provided with an arm 48 that extends horizontally toward the rear of the head. A pivot stud 50 extends through the arm 48 and is 40 fixed thereto in any suitable manner, as, for example, by being pressed into a hole formed in the arm to provide what is sometimes termed a drive fit. The stud 50 is arranged to turn in a suitable bearing in the frame 45 10 to enable the chopping knife to move from side to side, as hereinafter explained. The chopping knife is normally maintained in a median position, as shown by Fig. 2, and for this purpose the hub 52 of the arm 48 is provided with gear teeth 54 that mesh 50 with corresponding teeth 56 (Fig. 2) formed upon a rack member 58. This rack member is affixed by screws 60 to a laterally movable carriage comprising two members 62, 55 the connection between said members being formed, in part, by the rack member 58 and screws 60. The rack member, therefore, constitutes one member of the carriage, and it is arranged to slide endwise in a suitable 60 bearing formed in the frame 10. The forward ends of the members 62 are fixed to and connected by a rod 64, the latter being arranged to slide endwise in bearings 66 provided by the frame 10. The rear ends 65 of the members 62 are arranged between

and lapped by the free ends of two leaf springs 68, said springs being anchored to the frame 10 by screws 70. The stress of the right-hand spring 68 is applied to move the carriage to the left, and that of the left-hand spring is applied to move the carriage to the right. When the carriage occupies its median position, as shown by Fig. 2, the springs are seated on abutments 72 formed on the head, although their tips remain in contact with opposite faces of the carriage to maintain the latter in its median position.

In order to utilize the heel of the shoe to shift the chopping knife laterally from its median position to the desired path of chopping movement, the laterally movable carriage comprising the members 62 is provided with two feelers or work-engaging fingers 74. The lower ends of these fingers are arranged to be engaged and displaced 85 by the breast of the heel, although only one of them acts at any one time. The fingers 74 are arranged at opposite sides of the vertical median plane of the head, as indicated by dotted lines in Fig. 2. The right-hand finger, therefore, stands in the path of a heel approaching from the right, and the left-hand finger stands in the path of a heel approaching from the left. The upper ends of the fingers 74 are mounted to turn, for 90 the purpose of adjustment, in bearings formed in the members 62. Split collars 76 are clamped to the fingers and are connected by the springs 78 and arranged to draw the lower ends of the fingers toward each other. 100 Set screws 80 carried by the collars 76 are arranged to bear against portions of the members 62 to adjust the lower ends of the fingers by turning the fingers in their bearings. The split collars 76 are tightened by 105 screws 75 to clamp the fingers 74, but the latter may be adjusted up and down when the screws are loose. The tips of the fingers 74 may be adjusted toward the front or rear when screws 60 are loose, the members 62 110 having slots 63 to enable them to turn about the axis of rod 64.

When, in the course of trimming the shank of the sole, the breast of the heel displaces one of the fingers 74, the finger so 115 displaced remains, to all intents and purposes, rigid relatively to the laterally movable carriage that supports it, and the lateral motion is transmitted to the carriage through the set screws 80. The carriage is 120 thus shifted in the direction followed by the heel, the rack member 58 being thereby caused to swing the chopping knife guide 46 in the opposite direction to shift the chopping knife toward the approaching heel. The lateral shifting of the chopping knife is limited by stop-screws 81. The set screws 80 are intended to be adjusted to such positions that the maximum lateral movement of the chopping knife will carry 125 130

the latter to a path coincident with the limit to which the active edge of the shaving knife may cut. This shifting of the carriage flexes one of the leaf springs 68 from its 5 abutment 72, and when the heel is removed to release the finger 74, the leaf spring reacts to return the chopping knife to its normal or median position.

The chopping knife remains motionless in 10 its upper position whenever its carrier stands in the median position, and it does not begin to execute its chopping motion until it has reached one of its two limits of lateral movement. There are two actuators or ham- 15 mers for imparting chopping movement to the knife, one of which operates only when the knife is moved to the right and the other of which operates only when the knife is moved to the left. These two actuators, ac- 20 cording to the form shown, are levers 82 and 84. They are arranged to extend nearly horizontally, their rear ends being mounted on a fulcrum pin 86 supported by a portion of the frame 10. The forward ends of the 25 actuators are in the form of segmental heads indicated at 88 and 90 respectively. These heads are arranged to lie side by side in contiguous relation as shown by Figs. 2 and 4, and they are curved to be concentric rela- 30 tively to the axis of the stud 50 about which the chopping knife swings. A groove 92 is formed in the upper end of the chopping knife holder 42, and both heads 88 and 90 occupy this groove when the chopping knife 35 is in its median position. The actuators are thus locked relatively to each other. When, however, the chopping knife is moved laterally to one of its prescribed paths of 40 chopping movement the holder 42 moves entirely away from one of the actuators but remains in co-operative relation to the other. Guiding fixtures 94 and 96 mounted on the frame 10 are arranged to engage the outer face of the actuators to sustain the latter 45 against lateral stresses, the front faces of the heads 88 and 90 co-operating in this respect to sustain the actuators against stresses tending to move them toward each other. Springs 98 are connected to the actuators re- 50 spectively, to exert downward stress on them, said springs constituting means for imparting the chopping movement. Each actuator is thus arranged to operate independently of the other. The actuators are moved up- 55 wardly by cams 100 respectively, said cams being affixed to a shaft 102 extending through a suitable bearing in the frame 10 transversely of the shaft 12. A worm 104 formed on the latter shaft engages and drives a worm gear 60 106 fixed to the cam-shaft. In the present instance the cam-shaft is driven to rotate in a clockwise direction when viewed according to Fig. 1. The cams 100 are similar, in form, to ratchet wheels, each having a

plurality of high points to lift the actuator 65 a corresponding number of times in each revolution of the cam shaft. Motion is transmitted upwardly from each cam to the corresponding actuator by a thrust rod 108, the lower end of which is arranged to bear on 70 the working surface of the cam, and the upper end of which is in the form of a yoke and straddles a resilient connecting member 110. A pin 112 is arranged to connect the two branches of the yoke, and overlies the 75 member 110 to maintain operative connection between the latter and the rod 108. That portion of the resilient member 110 that occupies the yoke is suitably curved to compensate for angular movement of the 80 resilient member. The member 110 is fixed to the actuator 84 by screws 114, and may be flexed by a set screw 116 to adjust the actuator 84 relatively to the rod 108.

The lower end of the rod 108 has access 85 to its cam through an opening formed in an adjustable housing 118. This housing is clamped to the frame 10 by a screw 120, the latter extending through a segmental slot 122 in an ear formed on the housing. This 90 form of connection between the housing and the frame enables the housing to be adjusted rotatively about the axis of the cam, and its purpose is to advance or retract the lower end of the rod 108 relatively to the cam to 95 obtain the desired timing of the cam action. Inasmuch as the friction produced by the cam tends to swing the rod toward the rear the rod requires a bearing to keep it in co-operative relation to the cam, and for this 100 purpose the housing is provided with a hardened steel member 124 arranged to engage the rear face of the rod. A spring 126 is connected to the rod and is anchored to the frame 10 in position to hold the rod seated 105 against the bearing member 124. This form of bearing permits all necessary angular movement of the rod and permits the latter to be immediately withdrawn from co-operative relation to the cam as occasion may require. Although the actuators 84 are constantly under downward stress due to springs 110, the invention includes detents arranged to lock them in their upper positions so long as the chopping knife is between its two 115 prescribed paths of operative movement. These detents, however, are arranged to move laterally with the chopping knife to release whichever actuator is required to operate the chopping knife. In the present 120 instance the detents for this purpose are carried by the arm 48 of the chopping knife guide. As shown best by Fig. 3, the detents, which are indicated respectively at 130 and 132, are mounted one upon another, and each 125 embraces the upper end of stud 50 so that they may be adjusted toward and from each other about the axis of the stud. The detents

are clamped to arm 48 by clamping screws 134, and they are provided with segmental slots, one of which is indicated at 136, of sufficient length to permit the necessary 5 range of adjustment. The actuators 84 are provided with bosses 138 (see Figs. 1 and 4) which bosses are arranged to bear respectively on the detents 130, 132. In practice the detents will be adjusted to provide 10 a space between them of sufficient width to receive one boss 138 or the other, as the case may be, such space enabling the actuator with which it may be in registration to respond to the downward pull of the actuator 15 ing spring 98.

Whenever the chopping knife is shifted to its right-hand position, for example, to sever a shaving, detent 132 releases the right-hand actuator, but detent 130 continues 20 to underlie and support actuator 82. The latter, therefore, remains inactive in its raised position while actuator 84 responds to the action of spring 98 and that of the corresponding cam alternately. As soon, 25 however, as the breast of the heel releases the right-hand finger 74, the left-hand leaf spring 68 reacts to return the chopping knife to its median position. In the event of releasing the finger 74 while the actuator 30 84 is in any position other than its highest position, the return of the chopping knife to its median position will be postponed by interference between detent 132 and the boss 138 of the actuator then in use. In due 35 course, however, the actuator will be raised by its cam, and when it has risen far enough to release detent 132, the latter, together with all the other elements that are connected to move in unison incidentally to 40 the lateral shifting of the chopping knife, will respond to the stress of the left-hand leaf-spring 68, and the detent 132 will, therefore, move under the boss 138 of the actuator 84 and thereby lock the actuator in its upper 45 position where it will necessarily be in horizontal registration with the other actuator. This horizontal registration insures freedom of the chopping knife holder 42 to resume co-operative connection with actuator 82 without relinquishing co-operative 50 relation with actuator 84. The mechanism for operating the chopping knife is thus automatically rendered ineffective, but is rendered effective as occasion requires, by shifting 55 the chopping knife to the right or left.

Fig. 5, in addition to showing, by dotted lines, the range of movement of the shaving knife 16, includes full lines representing the chopping knife in its median position, and 60 dotted lines representing the chopping knife in each of its two prescribed paths of operating movement. It is to be observed that, whether the chopping knife be shifted to the right or to the left, its path of chopping

movement is coincidental with the corresponding limit of movement of the shaving knife. It follows, therefore, that both the shaving knife and the chopping knife will cut to a common point coincident with the breast line of the heel, provided the work-engaging members 74 are adjusted correctly for that purpose.

The stationary inseam guide 38 is shown as being mounted so that it may be moved away from operative position. It is desirable sometimes to retract the guide from the vicinity of the knives, as for example, to afford easy access to the knives, for adjustment or for detaching them from or attaching them to their respective holders. For 80 this reason the guide 38 is mounted on trunnions 140 by which it is connected to portions of the frame 10. The trunnions 140 are shown in the form of screws and they have threaded connection with the 85 frame. This construction enables the screws to be set up tightly to clamp the guide 38 in operative position, the guide being, nevertheless, capable of being moved away from operative position provided sufficient stress 90 is applied to it to overcome the friction due to clamping.

Having thus described my invention, what I claim as new and desire to secure by Letters Patent of the United States is:

1. A machine for operating on shoe-soles, comprising a knife for chopping the sole, means operable by a projection on the sole to shift the knife transversely of its lines of chopping movement so that it may operate in different paths, and means controlled by said shifting means to impart chopping movement to the knife.

2. A machine for operating on shoe-soles, comprising a chopping knife guide, a chopping knife arranged to slide in said guide, means arranged to impart chopping motion to the knife, and means operable by a projection on the sole to move the guide laterally so as to shift the knife to a predetermined path of chopping movement.

3. A machine for operating on shoe-soles, comprising chopping means including a chopping knife and mechanism arranged to operate the latter, means arranged to guide the knife to the sole, and means operable by the work to move said guiding means so as to shift the knife transversely of the lines of chopping movements.

4. A machine for operating on shoe-soles, comprising a knife arranged to be shiftable transversely of its lines of cutting movement, stops arranged to limit the transverse shifting of said knife so as to determine certain operating positions of the knife, and mechanism controlled by said shifting to operate said knife only in said certain positions.

5. In a machine of the character described, a chopping knife arranged to be movable transversely of its lines of chopping movement, controllable mechanism arranged to operate the knife, and means operable by a projection on the work to shift the knife transversely and to control said operating mechanism.

6. In a machine of the character described, means arranged to shave an edge of the sole of a shoe, a chopping knife arranged to be shifted laterally of its lines of chopping movement to and from a predetermined path of operation, and means arranged normally to 15 displace the knife laterally from said path.

7. In a machine of the character described, means arranged to shave an edge of the sole of a shoe, a chopping knife arranged to be shifted laterally of its lines of chopping movement to two predetermined paths of operation, and means arranged normally to shift said knife laterally from either one of said paths to an intermediate position.

8. In a machine of the character described, means arranged to shave an edge of the sole of a shoe, a chopping knife arranged to be shifted laterally of its lines of chopping movement to and from a predetermined path of operation, means arranged normally to shift the knife laterally from said path, and means controlled by said shifting means to impart operative movement to the knife only when the latter occupies said path.

9. In a machine of the character described, means arranged to shave an edge of the sole of a shoe, a chopping knife arranged to be shifted laterally of its lines of chopping movement to two predetermined paths of operation, means arranged normally to shift the knife laterally from either one of said paths to an intermediate position, and means controlled by said shifting means to impart operative movement to the knife only when the latter occupies one of said paths.

10. In a machine of the character described, chopping means including a chopping knife and mechanism arranged to operate the latter, a work-engaging member arranged to be moved by the breast of a heel attached to the work, and means arranged to shift the knife laterally in consequence of movement imparted to said member by the heel.

11. In a machine of the character described, chopping means including a chopping knife and mechanism arranged to operate the latter, a work-engaging member arranged to be moved by the breast of a heel attached to the work, and means arranged to transmit such movement of said member to shift the knife transversely of its path of chopping movement.

12. In a machine of the character described, a double-edged shaving knife and

mechanism arranged to reciprocate the same edgewise, a chopping knife arranged to chop the shaving formed by said shaving knife, and means arranged to shift said chopping knife laterally to paths of chopping movement coincident with the limits respectively of the path traversed by the shaving knife.

13. In a machine of the character described, a double-edged shaving knife and mechanism arranged to reciprocate the same edgewise, a chopping knife arranged to chop the shaving formed by said shaving knife, a pair of work-engaging members one of which is arranged to be displaced by the breast of the heel as the latter approaches the shaving knife from one side and the other of which is arranged to be displaced by the breast as the heel approaches the shaving knife from the opposite side, means operable by either of said work-engaging members to shift the chopping knife in a direction opposed to that of the approaching heel, and means arranged to operate the chopping knife.

14. In a machine of the character described, a chopping knife, a plurality of operating members relatively to which the chopping knife is movable transversely of its lines of chopping motion, means arranged to shift the knife transversely from co-operative relation with one of said operating members to co-operative relation with another, and means arranged to control said operating members so as to prevent operation of said knife while the latter is being shifted transversely.

15. In a machine of the character described, a chopping knife, a plurality of operating members relatively to which said knife is movable transversely of its lines of chopping motion, said knife and operating members having co-operative tongue-and-groove connecting portions by which the motion of the operating members, individually, is transmitted to the knife, and means arranged to shift the knife from co-operative relation with one of said members to co-operative relation with another.

16. In a machine of the character described, a chopping knife, independently movable hammers for operating said knife, hammer-operating mechanism, and mechanism arranged to shift the knife from one of the hammers to another and to prevent operating movement of the hammers excepting the one relatively to which the knife is temporarily in operative position.

17. In a machine of the character described, a chopping knife, hammers movable independently of each other to operate said knife, the latter being movable from one of the hammers to another, controllable mechanism arranged to operate the hammers one at a time, and means arranged to shift the knife to one of said hammers and

to render the hammer-operating mechanism operative as to the hammer to which the knife is shifted.

18. In a machine of the character described, 5 a chopping knife, hammers movable independently of each other to operate said knife, hammer-operating mechanism including yielding elements to permit the hammers to remain non-operative, controlling means 10 arranged to restrain the hammers from operating, and means arranged to shift the knife to one hammer or another and to move said controlling means to release the hammer relatively to which the knife is temporarily 15 in operative position.

19. In a machine having means for shaving an edge of the shank of the sole of a shoe, means for chopping the shaving at the breast of the heel, said chopping means comprising a reciprocatory knife movable about an axis substantially parallel to its lines of 20 chopping movement, and means arranged to shift the chopping knife about said axis to different paths for operating on right and 25 left edges.

20. In a machine for operating upon shoes, a tool arranged to be shifted to various predetermined positions to operate on the work, a work-engaging member and a support 30 therefor arranged to be moved by the work, means arranged to transmit motion from said support to shift said tool to one or another of said positions, and means arranged to operate the tool.

35 21. In a machine for operating upon shoes, a tool arranged to be shifted to various predetermined positions to operate on the work, means arranged to be moved by the work to shift the tool to one or another of said 40 positions, and controllable means, including a continuously driven element, arranged to be controlled by said tool-shifting means to initiate operation of the tool when the latter has been shifted to any one of said predetermined positions.

22. In a machine for operating upon shoes, a tool arranged to be shifted to various predetermined positions to operate on the work, means arranged to be moved by the work to 50 shift the tool to one or another of said positions, and means arranged to operate the tool, said tool-shifting means comprising a work-engaging member adjustable about axes extending transversely to each other.

55 23. In a machine for operating upon shoes, a tool movable to different positions for operating on right and left shoes, mechanism arranged to operate the tool in various positions, and means for controlling said operating mechanism, said tool being shiftable to different operating positions by said controlling means and the latter being movable by the work.

24. In a machine having means for shaving 60 an edge of the shank portion of the sole

of a shoe, means including a knife for chopping the shaving at the breast-line of the heel, and means for shifting the chopping knife to different positions for operating on right and left edges. 70

25. In a machine having means for shaving an edge of the shank portion of the sole of a shoe, means including a knife for chopping the shaving at the breast-line of the heel, and means for altering the angular 75 position of the chopping knife for operating on right and left edges.

26. In a machine having means for shaving an edge of the shank portion of the sole of a shoe, means including a knife for chopping the shaving at the breast-line of the heel, and means for shifting the chopping knife bodily and for altering its angle according to the pitch of the heel-breast to 80 operate on right and left edges. 85

27. In a machine having means for shaving an edge of the shank of the sole of a shoe, means for chopping the shaving at the breast of the heel, said chopping means comprising a reciprocatory knife movable bodily in lines 90 transverse to its lines of chopping movement to operate in different paths for right and left edges, and means operable by the breast of the heel for shifting the chopping knife to the path corresponding to the side 95 of the shoe presented for operation.

28. In a machine of the character described, a tool movable to one predetermined path for operating upon a right shoe and to another predetermined 100 path for operating upon a left shoe, means arranged normally to move said tool to an intermediate position between said two paths, mechanism constructed and arranged to operate said tool when the latter is in either 105 of said paths, and means controlled by the position of the tool to prevent operation thereof when the tool is in any other position than in one of said paths.

29. In a machine of the character described, a knife for chopping the edge of a sole at the breast of the heel, said knife being movable transversely of its lines of chopping movement to operate in different paths for right and left edges, the knife being 115 movable angularly to pitch the chopping cut according to the pitch of the heel-breast.

30. A machine for operating on shoes, comprising a work-engaging tool arranged initially outside the field of the work but 120 movable to different localities for operating on the work, mechanism arranged to operate said tool in each of its operating localities, and means controlled by the work so as to determine the locality at which said tool may 125 operate and to initiate operation of the tool in that locality.

31. In a machine of the character described, a chopping knife arranged to be shifted transversely to various operating po- 130

sitions, normally inoperative means for operating said knife, and means operable by or through the agency of the work for shifting said knife transversely and for rendering said operating means operative.

32. A machine for operating on shoes, comprising a working tool arranged to be shifted to a plurality of predetermined working localities and to execute working movement in each of said localities, means arranged to shift said knife to one or another of said localities, and tool-operating means arranged to impart working movement to said tool when the latter is in one of said predetermined localities, said shifting means be-

ing arranged to prevent operation of said tool when the latter is in any other locality than one of said predetermined localities.

33. A machine for operating on shoes, comprising a working tool arranged to be shifted to a predetermined working locality and to a non-working locality, mechanism arranged to operate said tool in said working locality, and means controlled by shifting said tool to prevent said mechanism from operating the tool in any intermediate position between the two aforesaid positions.

In testimony whereof I have signed my name to this specification.

FREDERICK H. PERRY.
